(57) CLAIM

The ornamental design for a headboard and footboard, as shown and described.

DESCRIPTION

FIG. 1 is a perspective view of a headboard and footboard showing my new design;

FIG. 2 is a front elevational view thereof; and,

FIG. 3 is a side elevational view, the opposite side being a mirror image thereof.

The views of the headboard and footboard not shown form no part of the claimed design. The broken lines depicting feet, nail heads, side rails and ornamentation on rails represent environmental elements only and form no part of the claimed design.
